Primary Examiner — Dana Meyrow*(74) Attorney, Agent, or Firm* — RMCK Law Group PLC(57) **CLAIM**

The ornamental design for an portion of closure for container, as shown and described.

DESCRIPTION

FIG. 1 is a top perspective view of a portion of closure for container in accordance with the present invention; FIG. 2 is a bottom perspective view thereof; FIG. 3 is a front elevation view thereof; FIG. 4 is a left side elevation view thereof; FIG. 5 is a rear elevation view thereof; FIG. 6 is a right side elevation view thereof; FIG. 7 is a top plan view thereof; FIG. 8 is a bottom plan view thereof; and, FIG. 9 is an exploded top perspective view of the portion of closure for container shown in use. The broken lines in the figures illustrate the portions of the design that form no part of the claimed design.
